(57) **CLAIM**

The ornamental design for a pod product case, as shown and described.

DESCRIPTION

FIG. 1 is an upper rear perspective view of a pod product case, showing the new design;

FIG. 2 is a lower front perspective view of a pod product case thereof;

FIG. 3 is front elevational view thereof;

FIG. 4 is a right elevational view thereof;

FIG. 5 is a rear elevational view thereof;

FIG. 6 is a left elevational view thereof;

FIG. 7 is a top plan view thereof; and,

FIG. 8 is a bottom plan view thereof.

The broken lines in the drawings depict portions of the pod product case that form no part of the claimed design.
